UNITED STATES PATENT OFFICE.

MORGAN EDWARD REES, OF MORRISTON, NEAR SWANSEA, WALES.

MEANS FOR SECURING RAILWAY-RAILS TO SLEEPERS.

1,377,928.

Specification of Letters Patent.

Patented May 10, 1921.

Application filed December 1, 1920. Serial No. 427,555.

To all whom it may concern:

Be it known that I, MORGAN EDWARD REES, a subject of the King of Great Britain, residing at Morriston, near Swansea, Glamorganshire, Wales, have invented new and useful Improved Means for Securing Railway-Rails to Sleepers, of which the following is a specification.

My invention relates to improved means for securing railway rails to sleepers, applicable to permanent way constructions employing sheet metal sleepers and rails having broad foot flanges resting directly on the sleepers without interposed chairs.

According to my said invention I provide a bolt or like member, the shank of which extends transversely of the rail below the sleeper and the ends of which pass through slots in the sleeper, these ends being suitably shaped, or provided with suitable means to clamp the rail to the sleeper. The part of the bolt which extends beneath the sleeper is bent or bowed so as to provide an upwardly directed elbow or crest which, when the nut at one end of the bolt is tightened, is drawn up against the underside of the sleeper which forms a fulcrum on which the bolt can rock, so that by tightening the nut at one end, the rail clamping means at the other end of the bolt is simultaneously caused to clamp the rail more firmly against the sleeper. By reason of the bolt being free to rock about this elbow or crest, when the nut at one end is tightened, both ends of the bolt act as springs to take up any slight slackening or yielding of the parts which may occur in use.

In combination with this improved bolt, I provide a clip or dog having a lug extending downwardly from the edge which rests upon the sleeper so that it can enter the slot in the sleeper through which the bolt projects. The length of the slots is such that the end walls thereof act as abutments for such lugs, or for the outer surface of the hooked end of the bolt, whereby the rail is positively held against lateral displacement in either direction.

In the accompanying drawings:—

Figure 1 shows a rail in transverse section and a side view of a bolt and clip comprised in the improved means for securing railway rails to sleepers.

Fig. 2 is a plan view of the same.

Fig. 3 is a view similar to Fig. 1 illustrating a modified form of the bolt and clip.

Figs. 4 and 5 are views similar to Figs. 1 and 2 illustrating a further modification of the bolt, hereinafter described.

As shown in Figs. 1 and 2, the rail *a* is secured to a sleeper *b* by a bolt *c* one end of which is hook shaped so that when this end has been introduced through a slot *d* in the sleeper, the lip *e* of the hook rests on the upper surface of the rail flange while the outside of the bend of the hook abuts against the outer end wall *f* of the slot *d*. When the hooked end of the bolt is in this position the shank of the bolt *c* extends underneath the sleeper to the opposite side of the rail where it is bent at an angle so that it extends above the sleeper through a slot *g* therein and through a hole in a clip or dog *h*. At this end the bolt is screw-threaded and provided with a nut *i*.

One edge of this clip or dog rests upon the sleeper while the opposite end is recessed or forked so as to provide two surfaces *j*, *k*, one of which rests on the upper surface of the rail flange and the other presses laterally against the edge of this flange. At a central or intermediate part of that edge of the clip *h* which rests on the sleeper a lug *l* is provided which extends downwardly into the slot *g* and bears against the outer wall *m* of this slot.

The part of the bolt *c* which extends beneath the sleeper is bent or bowed and arranged so that when the nut *i* is tightened the elbow or crest *n* of the bend or bow bears against the underside of the sleeper.

With this arrangement, when one edge of the clip *h* is resting on the sleeper and the surface *j* at the opposite end is resting on the rail flange and the intermediate part of the clip around the bolt is unsupported, if the nut *i* is tightened the clip is caused to clamp the flange on one side of the rail firmly to the sleeper. At the same time, owing to the bent or bowed shape of the bolt, the shank of the bolt acts like a lever whereby the hook shaped end of the bolt is caused to also clamp the flange on the opposite side of the rail firmly to the sleeper. The surface *k* on the clip bears against the edge of the flange of the rail and the lug *l* bears against the end wall of the slot *g* and together act as a wedge to press the rail against the inside of the hook on the opposite side of the rail which bears against the end wall of the slot *d*, so that the rail is thus held against displacement laterally on the

sleeper. Moreover the bent or bowed shank, in addition to acting like a lever, acts as a spring to keep the rail clamped to the sleeper even if the nut runs back a little owing to jarring or other causes.

The screw-threaded end of the bolt may be arranged to extend upwardly substantially parallel to the web of the rail as shown in Fig. 1 or it may be inclined with reference to the said web as shown in Fig. 3 in which case the clip or dog is formed with a suitably inclined upper surface σ for the nut i to bear against. The edge of the clip or dog which rests on the sleeper may have a bead p formed thereon as shown in Figs. 1 and 3.

In the modified arrangement shown in Figs. 4 and 5 both ends of the bolt c' are screw threaded and clips or dogs h as above described are provided at both ends of the bolt to clamp the flanges to the sleeper at points on opposite sides of the rail.

With this improved means for securing railway rails to sleepers the necessity of forming embossed or stamped up parts such as are usually provided in sheet metal sleepers to keep the rails properly spaced apart, is avoided, it being only necessary to form slots in the sleeper through which the bolts project, the dogs then acting to determine the position in which the rails are held.

What I claim is:—

1. A bolt for securing railway rails to sleepers, comprising a shank adapted to be arranged beneath the sleeper transversely to the rail and bent so as to provide an upwardly directed elbow to bear against the underside of the sleeper, and having end portions adapted to project through the sleeper on opposite sides of the rail and provided with means for clamping the rail flange to the sleeper.

2. Means for securing railway rails to sleepers, comprising a bolt having a bent shank providing an upwardly directed elbow arranged beneath the sleeper and having ends projecting through the sleeper, one of the said ends of the bolt having a hook arranged so that the lip of the hook rests on the rail flange on one side of the rail and the other end of the bolt being screw-threaded, a clip mounted on said screw-threaded end, and a nut for clamping the said clip against the rail flange on the other side of the said rail.

3. Means for securing railway rails to sleepers, comprising a bolt having a bent shank providing an upwardly extending elbow arranged beneath the sleeper, and having its ends adapted to project through the sleeper, one end of the bolt being screw threaded to receive a nut, and a clip which can be clamped on the rail flange by the said nut.

4. Means for securing railway rails to sleepers, comprising a bolt having a bent shank providing an upwardly extending elbow arranged beneath the sleeper and having its ends adapted to project through the sleeper, having one of its ends screw threaded to receive a nut, and a clip having a bead to bear on the sleeper.

5. Means for securing railway rails to sleepers, comprising a bolt having a bent shank providing an upwardly extending elbow arranged beneath the sleeper and ends projecting through the sleeper, one end of the bolt being screw threaded to receive a nut, a clip provided with a bead to bear on the sleeper and having angularly disposed surfaces bearing respectively on the upper and lateral surfaces of the rail flange.

6. Means for securing railway rails to sleepers, comprising a bolt having a bent shank providing an upwardly extending elbow arranged beneath the sleeper and having its ends adapted to project upwardly through slots in the sleeper and to abut against the ends of the said slots one end of said bolt being screw threaded to receive a clip and a nut on said screw threaded end for clamping the clip against the rail flange.

7. Means for securing railway rails to sleepers comprising a bolt having a bent shank providing an upwardly extending elbow arranged beneath the sleeper and having its ends adapted to project upwardly through slots in the sleeper, one end of the bolt being screw threaded to receive a nut, a clip mounted on said screw threaded end and having a lug adapted to extend downwardly from said clip into the slot in the sleeper through which this end of the bolt passes.

MORGAN EDWARD REES.
